(57) **CLAIM**

The ornamental design for a cap for travel trailer, as shown and described.

DESCRIPTION

FIG. 1 is a perspective view of a cap for travel trailer illustrating our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is a right side elevational view of FIG. 6, wherein a recess cover is in a partially opened orientation, the left side being a mirror image;

FIG. 9 is a perspective view of the cap for travel trailer of FIG. 1 shown attached to a travel trailer;

FIG. 10 is a front elevational view thereof;

FIG. 11 is a rear elevational view thereof;

FIG. 12 is a top plan view thereof;

FIG. 13 is a bottom plan view thereof;

FIG. 14 is a right side elevational view thereof; and,

FIG. 15 is a left side elevational view thereof.

The broken lines shown in the figures are for illustrative purposes only and form no part of the claimed design.
